UNITED STATES PATENT OFFICE.

RICHARD F. STEWART, OF ELMNSFORD, NEW YORK.

INCINERATOR.

1,261,313.

Specification of Letters Patent.

Patented Apr. 2, 1918.

Application filed September 20, 1916. Serial No. 121,200.

To all whom it may concern:

Be it known that I, RICHARD F. STEWART, a citizen of the United States, residing at Elmsford, in the county of Westchester and

5 State of New York, have invented new and useful Improvements in Incinerators, of which the following is a specification.

This invention relates to incinerators adapted more particularly for domestic use 10 in the burning of garbage or other refuse.

One of the main objects of this invention is to provide a device which will serve as an ordinary can or receptacle for the collection of garbage or other refuse, and which may 15 also be employed as an incinerator in which the collected refuse may be destroyed by burning. The incinerator is made in a compact form and is relatively light in weight, so that it may be placed in a sink or other 20 convenient place when utilized as a garbage receptacle, and easily carried and placed upon a heater or stove when it is desired to burn the garbage which has collected within the incinerator.

25 Further objects of the invention are to provide a simple and efficient structure which may be manufactured at a minimum cost, so that it will be within the reach of persons of ordinary means; to provide a device in which 30 the garbage is burned to an ash and in which all odors of the burning garbage or other refuse are eliminated; to provide a device which is substantially air tight when used as a garbage receptacle or as an incinerator, 35 so that contagious germs, flies or other insects will not be attracted by the garbage and obnoxious odors will not pollute the air of the kitchen or room in which the device is located; and to provide a device in which 40 the garbage may be burned after each meal, or at regular frequent intervals, thereby eliminating the annoyance and inconvenience resulting from collectors gathering the garbage at long intervals.

45 The above and other objects of my invention are obtained by the structure described in the following specification and illustrated in the accompanying drawings, and where- in—

50 Figure 1 is an elevational view of my improved incinerator, the same being illustrated as located upon a stove, only so much of the stove and the flue or pipe thereof being shown as is necessary to disclose the application of the incinerator thereto.

Fig. 2 is a top plan view of the structure shown in Fig. 1.

Fig. 3 is a vertical sectional view taken centrally through the incinerator.

Fig. 4 is an elevational rear view of the 60 incinerator.

Referring to the drawings wherein like numerals represent like parts in the several views, 10 designates my incinerator which, as shown in Figs. 1 and 2, may be mounted 65 over one of the holes in the top of a stove 11 having a stove pipe section 12, in the present instance, the stove being shown more or less conventionally as it forms no part of my invention. It is to be understood that the incinerator may be used in combination with any form of heater apparatus, such, for instance, as a coal, gas, electric or oil stove.

The incinerator 10 has a body portion 13 composed of sheet metal and comprising, in 75 the present instance, an open ended receptacle, cylindrical in cross-section. The body portion 13 is provided along its top edge with an external wire bead 14, while its lower end is provided with an internal wire 80 bead 15.

16 designates the bottom of the incinerator which forms a grate upon which the garbage or other refuse is burned. This bottom 16 is in the form of an inverted funnel having a conical body portion and a stem portion 17 extending from the apex of the conical portion upwardly and centrally of the incinerator. The bottom portion 16 together with the stem 17 are 85 provided with perforations or openings over their entire surfaces, these openings or perforations being of such size as to prevent the garbage from falling through the bottom of the incinerator, but, at the same time, 90 permitting a draft upwardly through the garbage within the receptacle. The bottom 16 is preferably formed of sheet metal, so that it may be produced at a minimum cost and is relatively light in weight. The 100 diameter of the open end of the bottom 16 is substantially the same as the internal diameter of the body portion 13 of the incinerator, so that it may rest upon the flange or wire bead 15.

The incinerator 10 is provided with a flue pipe 18 which is attached to the body portion 13 adjacent its upper edge. In the present instance, the flue pipe 18 is disclosed as in the form of an elbow so as to permit 110

the incinerator to be placed over one of the side holes of the stove 11, but it is to be understood that the flue pipe may extend radially from the body portion of the incinerator when it is desired to place the device over a stove hole which is immediately in front of the stove pipe.

19 designates a lid or cover which, in the present instance, is disclosed as having a 10 depending flange 20 adapted to fit snugly within the open end of the receptacle, as shown in Fig. 3, so as to prevent the escape of obnoxious odors, fumes or smoke from the incinerator and prevent flies, insects, 15 and the like, from gaining access to the interior thereof. The lid is provided with a handle 21 to permit of its ready removal from the incinerator. When the flue pipe 18 is not connected to the pipe of the stove, it 20 is closed by means of a cover 22 which is similar in structure to the lid or cover 19 heretofore described. To permit the incinerator to be readily lifted to and from the stove, it is provided with a pair of 25 diametrically disposed handles 23, which may be of any suitable or approved type, those shown in the drawings being by way of illustration only.

When the incinerator 10 is used as a receptacle for receiving garbage, it is set aside in some convenient place, with the covers 19 and 22 over its top and flue pipe, as shown in Figs. 3 and 4, and, preferably, it is set upon a shallow pan 24, as shown in 30 Fig. 3, so that if any wet garbage is placed in the incinerator, the pan will catch and hold any drippings resulting therefrom. When it is desired to burn the garbage which is collected within the receptacle, the 35 incinerator is removed from the shallow pan 24 and placed upon the stove immediately over one of the stove holes, and the flue pipe 18 of the incinerator is connected up with the stove pipe 12 as shown in Figs. 1 and 2. The stove pipe has a damper 25 which is located immediately beneath the point at 40 which the flue pipe of the incinerator is connected with the stove pipe, and this damper is turned into shut-off position during 45 the burning of the garbage, so that a direct draft is obtained through the incinerator, and that portion of the stove-pipe above the damper.

During the incinerating operation, the 50 heated gases and products of combustion from the fire in the stove over which the device is located pass upwardly through the grate or bottom 16 and dry and burn the garbage thereon. As the grate is in the 55 form of a cone, there is a tendency for the garbage to move outwardly toward the walls of the receptacle leaving the garbage above the central portion of the grate loosely packed and thus permitting of a central 60 draft opening through the receptacle and

the likelihood of the grate becoming clogged by the packing of the garbage is eliminated. The stem or perforated pipe 17 provides a centrally disposed passageway or flue which also serves to maintain a draft opening 70 through the garbage, and this is of particular advantage when the garbage is wet, and, therefore tends to pack. By the arrangement just described, the gases pass upwardly through the bottom of the grate and heat 75 the garbage thereon to the point of combustion, and thus cause consumption of the same. Some of the gases, or heated products of combustion, pass into the stem 17 and are drawn or forced by the draft obtaining 80 through the flue pipe 18 in the stove pipe 11 through the garbage. Thus the garbage in the upper portion of the can is dried out as the mass of the garbage gradually sinks in the receptacle, due to the burning of the 85 garbage in the bottom of the incinerator, when the upper portion of the garbage reaches the bottom of the incinerator, it is in condition to be burned to an ash.

It will be noted that my device comprises 90 but a relatively few number of parts which may be constructed of sheet metal, and which are, therefore, relatively light so that the incinerator may be readily placed upon and removed from a position over the stove-hole 95 of a heater. The device may be manufactured at a relatively low cost, so that it may go into universal use in the homes of people in moderate circumstances.

It is, of course, obvious that my invention 100 is susceptible of various modifications and changes which would be within the spirit of the invention without departing from the scope of the following claims.

What I claim is:

1. In an incinerator, a portable open-ended casing, a flue opening in said casing, an internal beaded flange adjacent to the bottom edge of said casing, an inverted funnel shaped bottom detachably supported by said flange, said bottom having a central draft opening, the bottom and draft opening being perforated substantially throughout their 110 entire surfaces.

2. The combination in a portable incinerator of a casing having means for connecting it to a draft pipe and an open lower end adapted to be brought into communication with the stove opening, an inverted funnel shaped structure adapted to be detachably supported within the receptacle near its lower end, said structure perforated substantially throughout its entire surface and a detachable imperforate cover for said lower end whereby said receptacle may be used as 120 a garbage receiver when not in use as an incinerator.

3. In combination a heater, a stove pipe for said heater, a damper in said pipe and a portable incinerator adapted to be placed 125

upon or removed from said heater, said incinerator comprising a portable open-ended casing, a flue opening in said casing adapted to be connected to the stove pipe above said damper, a foraminated inverted funnel shaped structure adapted to form a bottom for said casing, said funnel shaped structure having a central draft passage-way.

10 4. In combination, a heater, a stove pipe for said heater, a damper in said pipe and a portable incinerator adapted to be placed upon and removed from the heater, said incinerator comprising a combustion chamber 15 having an open lower end adapted to be

brought into communication with the opening on the heater, a flue pipe adapted to be connected to the stove pipe above said damper, a detachable cover for the upper end of said chamber, a bottom for the lower end comprising an inverted funnel shaped structure supported solely by inwardly projecting means at the bottom of the chamber.

5 In testimony whereof I have hereunto set my hand in presence of two subscribing witnesses.

RICHARD F. STEWART.
